UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

SEPARABLE FASTENER.

1,156,008.

Specification of Letters Patent

Patented Oct. 5, 1915.

Application filed March 27, 1915. Serial No. 17,815.

To all whom it may concern:

Be it known that I, ERNEST N. HUMPHREY, a citizen of the United States, residing at New Britain, county of Hartford, State of Connecticut, have invented certain new and useful Improvements in Separable Fasteners, of which the following is a full, clear, and exact description.

This invention relates to separable fasteners of the "cast-off" type used in the suspender construction. Such a fastener is designed to permit the strap and cord to be readily attached and detached, when the invention is embodied in suspenders of standard construction. A preferable embodiment of the invention in a "cast-off" of this character is described in detail in the following specification and taken in connection with the accompanying drawings.

20 In these drawings: Figure 1 is a view in front elevation of a suspender cast-off constructed in accordance with the present invention. Fig. 2 is a similar view but with the parts separated. Fig. 3 is a vertical sectional view on the line 3—3 of Fig. 1. Figs. 4 and 5 show the separate parts of one form of cast-off.

Referring to the drawings by numerals, 1 indicates the front end of a suspender shoulder strap, the lower end of this strap running through a slotted plate 2 forming one of the two separable members of the cast-off. This plate is provided with a downward extension 3 having a slot 4 therein, the width 30 of this slot being restricted from intermediate its ends to the lower end, so that in general configuration, it is suggestive of a key-hole. At the point where the restriction begins, the face of the plate 3 is formed with oppositely disposed raised abutment members 5, these being positioned at opposite sides of the slot. The outer separable part 40 in this case comprises the cord guide member with attaching means. This other part is preferably formed as follows: I provide a strip of sheet metal bent to form a cord guide 6, the sides of said cord guide at its upper end being joined as at 7. This upper end carries rigidly a stud 8 projecting outwardly therefrom at substantially right angles and having a head 9 at its outer end. This head is of a diameter to permit its insertion through the large end of the slot 4, its shank being sufficiently small to extend 50 within the restricted portion of the slot, but

its head being of too great diameter to pass between the raised abutment 5, although it may pass over and beyond the same and rest therebelow with the shank resting substantially at the restricted end of the slot. I 60 interpose a spring between the cord guide and the slotted plate. The spring normally tends to hold the head of the stud against the plate and in line with the raised abutments 5. The spring, however, may yield under 65 pressure to enable the head of the stud to pass over the abutments 5 from one end of the slot to the other, thus permitting the stud to be inserted and removed. This spring is preferably formed separate from 70 the cord guide, as this enables heavier stock to be used for the cord guide, a light spring stock being difficult to bend into a cord guide without breaking. Therefore, I provide a U-shaped leaf spring 10, one end of which is 75 rigidly secured to the upper end of the cord guide when the stud 8 is fixed thereto, preferably the end of the stud being riveted over the attached spring clip. The opposite arm of the spring is provided with an aperture 80 through which the rear end of the stud 8 is inserted before riveting. This aperture is sufficient to allow the spring arm to move back and forth upon the shank of the stud. The action of the spring is to normally extend the cord guide rearwardly and, therefore, move the head 9 of the stud rearwardly. Consequently, as will be seen from Fig. 2 85 of the drawings, when the head of the stud is inserted in the enlarged end of the slot 4 and moved downwardly, its under face will engage the raised abutments 5. As the stud is moved still farther downwardly, the spring 10 will be compressed permitting the stud to pass over the abutments to the position below the abutments shown in Fig. 2. In this position the parts are detachably interlocked, as the head of the stud lies in line with the abutment and may not pass upwardly thereover except the spring 10 be 90 compressed by hand and the stud intentionally moved. The pressure of this spring is amply sufficient under ordinary circumstances to prevent accidental unlocking.

What I claim, therefore, and desire to secure by Letters Patent is:

1. In combination, two separable parts, one comprising a plate having a key-hole slot therein, an abutment on said plate at each side of said slot, and adjacent to the 110

middle portion thereof, the other member comprising a plate shaped to form a curved tubular bearing at its lower end, a stud rigidly connected to the upper end thereof,
5 the diameter of the stud head being greater than the narrower portion of the key-hole slot and sufficiently great to engage the abutments at opposite sides thereof, and a spring located between said stud head and the up-
10 per part of the second member to which the stud is attached, said spring operating to draw the back of the stud head against the front face of the first member when said parts are attached.
15 2. In combination, two separable parts, one comprising a plate having a key-hole slot therein, an abutment on said plate at each side of said slot, and adjacent to the middle portion thereof, the other member comprising a plate shaped to form a curved tubular bearing at its lower end, a stud rigidly connected to the upper end thereof, the diameter of the stud head being greater than the narrower portion of the key-hole slot and sufficiently great to engage the abutments at opposite sides thereof, and a spring located between said stud head and

the upper part of the second member to which the stud is attached, said spring operating to draw the back of the stud head against the front face of the first member when said parts are attached, said spring stud and second mentioned plate being rigidly united at a common point. 30

3. In combination, two separable parts, 35
one comprising a plate having a key-hole
slot therein, an abutment on said plate at
each side of said slot and adjacent the
middle portion thereof, the other member
40 comprising a plate shaped to form a curved
cord bearing at its lower end, a stud rigidly
connected to the upper part thereof and
projecting forwardly therefrom, the diam-
eter of the stud head being greater than the
narrower portion of the key-hole slot, and a
45 spring located between the stud head and
that part of the second member to which the
stud is attached, said first mentioned plate
being arranged to occupy the space between
said spring and said stud head when the
50 parts are assembled, said abutments offering
resistance to the attachment and detachment
of said separable parts.

ERNEST N. HUMPHREY.
